UNITED STATES PATENT OFFICE.

FRANK B. DAVIDSON, OF MARSEILLES, ILLINOIS, ASSIGNOR TO HOWE AND DAVIDSON COMPANY, OF EAST ORANGE, NEW JERSEY, A CORPORATION OF NEW JERSEY.

PAPER-BOARD BOX.

No. 890,222.

Specification of Letters Patent. Patented June 9, 1908.

Application filed January 31, 1907. Serial No. 255,076.

To all whom it may concern:

Be it known that I, FRANK B. DAVIDSON, a citizen of the United States, and a resident of Marseilles, in the county of Lasalle and State of Illinois, have invented certain new and useful Improvements in Paper-Board Boxes; and I do hereby declare that the following is a full, clear, and exact description thereof, reference being had to the accompanying drawings, and to the letters of reference marked thereon, which form a part of this specification.

This invention relates to improvements in paper-board boxes of that type made from a single sheet of paper-board or like sheet material cut and scored to define wall members and interlocking flaps that are folded upwardly from the body of the blank to constitute the walls of the box.

Among the objects of my invention is to provide an improved construction in boxes of this character designed to strengthen the connection between the meeting walls at the corners of the box, and the invention consists in the matters hereinafter set forth and more particularly pointed out in the appended claims.

In the drawings:—Figure 1 is a plan view of one form of blank from which my improved box is made. Fig. 2 is a perspective view of the set-up box. Figs. 3 and 4 are fragmentary, perspective views of one corner of the box, as viewed from within, showing two positions which the wall sections and flaps assume while being folded upwardly to form the walls. Fig. 5 is a perspective view of one of the finished corners of the box, as viewed from within. Fig. 6 is an enlarged horizontal section, taken on line 6—6 of Fig. 5. Figs. 7 and 8 are vertical sections taken on lines 7—7 and 8—8, respectively, of Fig. 5. Fig. 9 is a plan view of a modified form of blank. Figs. 10 and 11 are fragmentary perspective views of one corner of the box, as viewed from within, showing two positions of the parts while being folded to form the walls. Fig. 12 is a perspective view of the inner side of one corner of the box. Fig. 13 is a perspective view of the exterior corner of the box. Figs. 14 and 15 are vertical sections taken on lines 14—14 and 15—15, respectively, of Fig. 12. Fig. 16 is a horizontal section, taken on line 16—16 of Fig. 12.

The box herein shown as embodying my improvements comprises a central body por-

tion and surrounding side and end walls, and may constitute the body of a box adapted to be closed by a flanged lid or cover of like or other construction, or the box herein shown may, in itself, constitute the lid or cover of an open ended box. The improvements herein disclosed relate more specifically to the construction by which the meeting walls of the box are joined.

The blanks from which the two forms of box herein shown are made are alike with the exception of certain variations of the flaps at the corners of the box. Like parts of both forms of box, therefore, bear the same reference characters, different reference characters being applied to the parts shown in Figs. 9 to 16, inclusive, which differ from the like parts shown in other figures.

The blank is made from a single rectangular sheet of paper-board and is herein shown as an oblong rectangle. A designates the body of the blank, and A¹ A¹ and A² A² the side and end wall sections respectively, divided from the body of the blank by score-lines a a¹, respectively. Formed integral with the end wall sections are terminal flaps A³ A³ which are divided from the end wall sections by score-lines a² a². The side wall sections A¹ are provided at their ends with triangular folding flaps A⁴ which are divided at their bases from said side wall sections by score-lines a³ a³. In the form of box shown in Figs. 1 to 8, inclusive, the end wall sections are provided with like triangular flaps A⁵ divided along their bases from the end wall sections by score-lines a⁴, and separated from the other triangular flaps A⁴ by oblique lines of severance a⁵. The two triangular flaps A⁴ A⁵ at each corner of the blank constitute a rectangular section that fills the angle between the adjacent side and end wall sections A¹ and A². The said terminal flaps A³ are provided at their ends with rectangular flaps or extensions A⁶ A⁶ divided from the terminal flaps by score-lines a⁶ a⁶. Said extension flaps A⁶ are made integral with the adjacent triangular flaps A⁵ and are divided therefrom by score-lines a⁷.

In the complete or set-up box, as shown in Fig. 2, the side and end walls A¹ A² are disposed at right angles to the body portion A in the usual manner. The terminal flaps A³ fit within the box in contact with the inner faces of the end walls A², thereby forming end walls of double thickness. When said

terminal flaps A^3 are made of the same width as the end wall sections, the free margins of said flaps extend entirely to the bottom of the box as shown in Fig. 2. The width of said terminal flaps may be varied, however. The triangular flaps A^4 of the side walls of the box occupy the spaces between the end walls and the terminal flaps A^3 , as best shown in Figs. 6 and 7. The extension flaps A^6 fit inside of and in contact with the inner faces of the side walls of the box at the ends of said walls, while the triangular flaps A^5 , being integral with the end wall sections and said extension flaps, fit outside of and in contact with the outer faces of the side walls at the ends thereof, as shown in Figs. 2, 6 and 8.

In folding the blank as shown in Fig. 1 to set-up the box, the side walls are first folded upwardly and thereafter the triangular flaps A^4 are turned inwardly at right angles to the side wall sections. The end wall sections are then folded upwardly against said inturned triangular flaps A^4 , as indicated in Fig. 3. Thereafter the terminal flaps A^3 are folded downwardly and inwardly against the inner faces of the end walls and the inturned flaps A^4 , said flaps folding about the score-lines a^2 . At this time, by reason of the integrality of the extension flaps A^6 with the terminal flaps A^3 , said extension flaps are folded downwardly inside the side walls, as indicated in Fig. 4, and when the terminal flaps are folded in place, the said extension flaps are brought to their final positions flat against the inner faces of the side walls, and at right angles to the said terminal flaps, as shown in Figs. 5 and 6. Furthermore, by reason of the integrality of the flaps A^5 and A^6 , when said extension flaps A^6 are thus folded downwardly and inwardly against the inner faces of the side walls, the said flaps A^5 are swung inwardly against the outer faces of the side walls, as shown in Fig. 2, the said integral flaps folding about the upper margins of the side walls along the scored or folding lines a^7 . When the blank is made of relatively stiff or heavy paper or fiber-board, it is desirable to give to the rectangular extension flaps A^6 some flexibility in order that they may be readily folded or tucked downwardly into the corners of the box without liability of placing such strain upon the folding parts as will tend to distort or tear the same. To this end said flaps A^6 are shown in the drawings as being weakened by score-lines a^8 extending diagonally across the same. The same effect may, however, be produced by otherwise scoring or lessening the stiffness of said flap.

The construction and arrangement of the wall sections and corner interfolding flaps set forth, produces an extremely rigid construction of the box at the corners thereof, it being observed from an inspection of Fig. 6, that each corner of the box includes three layers

of material; two of said layers consisting of the flaps A^4 A^5 , each made integral with one of the meeting walls and overlapping the adjacent wall, and the third layer being formed by the terminal or extension flaps A^6 . The box has, therefore, great capacity to withstand at the corners thereof, lateral pressure tending to crush the same inwardly, and also to withstand pressure in the direction of the planes of said overlapping parts, tending to crush the same downwardly. When a complete box is composed of two telescopic members like that shown in Fig. 2, the corners of the box will be further strengthened by the addition of three additional layers of material, thereby providing very great strength at these points with an economy in the quantity of material used in the construction of the box. Moreover, it will be observed that the construction described in the overlapping parts at the box corners, produces a joint which maintains parts constituting the box corners in interlocked relation without requiring special fastening means to hold the same in position. It will be observed in this connection that the ends of the side walls of the box are embraced between the folded flaps A^5 A^6 and said side walls cannot swing outwardly until the terminal flaps A^3 and their extension flaps are raised out of their locking positions. It will be furthermore observed that no strains brought on the box in the use thereof will have any tendency to lift or throw said terminal and extension flaps out of their said locking positions.

In Figs. 9 to 16, inclusive, is shown a form of box wherein the interfolding flaps at the corners thereof are designed to be fastened together by paste or other fastening means. This form of blank differs from that shown in Figs. 1 to 8, inclusive, in that the extension flaps A^7 , corresponding with the extension flaps A^6 hereinbefore described, are separated from the triangular flaps A^8 , corresponding with the flaps A^5 , by lines of severance a^9 . The interfolding parts of the box shown in Figs. 9 to 16, inclusive, occupy generally similar relations to each other as in the construction previously described. By reason of the separation, in this form of box, of the extension flaps A^7 and A^8 , it is necessary to provide some means for fastening at least the flaps A^7 and A^8 to the wall sections. Such fastening of the flaps may be effected by the use of suitable clips or staples, or paste may be applied thereto whereby said flaps are caused to adhere to the parts against which they fold, when the box is set-up. By reason of the arrangement of said flaps at the corners of the blank, paste may be readily applied at one time to all of the flaps at each corner, as indicated at a^{10} , and, when said flaps are folded upwardly against the wall sections, each of the flaps will adhere and will

be permanently secured to the part against which it is folded.

Reference is herein made to certain walls of the box as side and end walls for convenience only in describing the box illustrated, and the use of the terms mentioned is not intended to limit the invention to a box having the oblong rectangular form shown, it being obvious that the features of construction 10 constituting my invention may be embodied in a box in which the walls herein called the end walls may be longer than what are herein called the side walls, or to a square box or one in which the walls are all of the same length.

15 I claim as my invention:

In a paper box two walls meeting at an angle, a terminal flap integral with one of the walls and which is folded against the inner

face of said wall, triangular folding flaps on the meeting edges of said walls, one of said flaps occupying the space between the terminal flap bearing wall and the terminal flap thereon and the other resting against the outer face of the other wall, and an integral extension flap on the end of the terminal flap 20 which is folded at right angles to said terminal flap and rests against the inner face of said latter wall.

In testimony, that I claim the foregoing as my invention I affix my signature in the presence of two witnesses, this 28th day of January A. D. 1907.

FRANK B. DAVIDSON.
